DUPLEX CLIPPERS

Filed June 13, 1936

INVENTOR.

Godfrey Kotzin

UNITED STATES PATENT OFFICE

2,125,575

DUPLEX CLIPPERS

Godfrey Kotzin, Los Angeles, Calif.

Application June 13, 1936, Serial No. 85,113

5 Claims. (Cl. 30—212)

This invention relates to improvements in mechanism for operating duplex hair clippers and has for its object to provide a simple, efficient and inexpensive means for reciprocating the angularly disposed set of hair cutting clippers which forms a vital feature of my new duplex clippers.

With the above and other objects in view my invention consists in the construction and arrangement of parts disclosed in the drawing and specification and then more particularly pointed out in the appended claims.

In the drawing, wherein similar reference characters designate similar parts throughout the respective views,

15 Figure 1 is a plan view of one form of my invention, partly in section,

Figure 2 is a sectional view of the clipper comb showing the clipper blades mounted angularly thereupon,

20 Figure 3 is a rear elevation of my invention,

Figure 4 is a plan view, largely in section of another type of my invention to be described,

Figure 5 is a cross section taken through the comb and its associated blade to be described, on line B—B of Figure 4, looking in the direction of the arrow,

Figure 6 is a diagrammatic view showing the position of the angular clippers of my implement upon a head,

25 Figure 7 is a top plan view of Figure 4,

Figure 8 is a side elevation of Figure 4,

Figure 9 is a front elevation of Figure 4,

Figure 10 is a front elevation of Figure 4,

Figure 11 is a fragmental sectional elevation of 30 the casing showing the interior parts of the comb and blades, taken on line C—C of Figure 7 looking in the direction of the arrows, and

Figure 12 is a rear elevation of Figure 4.

In accordance with my invention I disclose a 35 hair cutting implement characterized by the fact that it is provided with an angular V-shaped comb upon whose divergent sides two cutter clippers are mounted for simultaneous movement. I also provide mechanism designed to impart 40 movement to these two angularly disposed clippers.

One form of mechanism is disclosed in Figures 1 and 3, and another form in the remaining figures.

45 The implement has a case 10 hollow within as at 11; having a slot at its rear as at 12 through which projects a movable handle bar 13 whose innermost lever end 14 forms a V with another and integral lever 15 whose apex is located where 50 the pivot pin 16 is, the latter being journaled in

a fixed bearing 17 within the casing. Handle bar 13 is thus mounted upon pivot pin 16 as a fulcrum so as to swing thereupon. A fixed curved handle bar 19 is formed upon casing 10, and projects in confronting relationship with respect to handle bar 13.

5 The V-shaped clipper comb has divergent sides 21, 28 formed with cutter teeth, and the pair of identically similar cutting clipper blades 24, 25 are slidably mounted upon these sides, carrying for this purpose, integral tongues 49 which slide in elongated grooves or tracks 50 formed upon the angular sides of the comb; the flat angular terminal cheeks 29 and 30 of the casing 10 confine the blades in the comb and against displacement therefrom; the oppositely terminal lugs or extremities of the comb overlie flat adjacent parts of the casing thereby permitting set screws or the like fasteners 41 to removably secure the casing upon the comb.

15 Pins on levers 14, 15 are designated respectively 20, 21 and project in slotted ears or pairs of spaced pins 22, 23 projecting outwardly from the clipper blades 24, 25; it will be noted when pin 21 of lever 14 is disposed at the outer end of the ear or pair of pins 23, pin 20 of lever 15 is disposed at the inner end of ear or pair of pins 22. Hence when 20 both handle bars 13, 19 are squeezed and drawn towards each other cranks or levers 14, 15 move

25 both blades reciprocatingly in the same direction; the swinging handle bar 13 has a curved lug 31 in whose socket 32 is fitted a curved post 33 carried by an ear 34 fixed within casing 10; a contractile spring P is secured at one end to lug 31 and is also coiled around post 33 and secured thereto.

30 This spring is put under tension when handle bars 13, 19 are squeezed; during the reciprocation of the two blades hairs are cut which extend from end to end of the comb teeth, the operator applying pressure in one direction upon the handle bars while the spring 33 applies pressure upon them in a counter direction. The casing 10 has its top closed by means of a flat wall 10' shown in Fig. 7; and the oppositely slanting front edges of 35 this wall 10' are designated respectively X and Y and are spaced in parallel relation from the similarly sloping combs of the casing to provide a slit.

35 The form of mechanism and implement shown in Figures 4 to 12 will now be described. Here 40 the casing is mounted with respect to the angular sides of the comb with the positioned blades in the same manner just now described in connection with Figure 1. However the mechanism for imparting reciprocating movement to both blades 45

50

55

55

is such as to cause the blades to move towards and from each other instead of in the same direction. The curved handle bars 35, 36 project into slot 12 of casing 10, being crossed herein and mortised as at S to permit a pin 39 to pivot both bars together so they rest upon bridging arm 36' in this slot, this pin 39 passing thru this arm and an ear 37 upon casing 10. The handle bars 35 and 36 have integral hook-shaped finger holds 48. The inner ends of the bars 35, 36 are pivoted by pins 47 to the outer ends of crossed bell-crank levers 44, 45 which are pivoted at 46' together, and which have outermost pins 43 projecting into slotted ears 42 carried respectively by blades 24, 25, whose teeth 26 have the usual cutting edges. When the two handle bars are squeezed and pressed together in one direction, spring 46 separating the pivoted ends of bars 35, 36 and levers 44, 45 is compressed, and then levers 44, 45 swing to separate the blades slidably so the hairs that previously entered the registering recesses of comb 10 designated M and those designated N of the blades are now cut as the blades are side swiped; when spring 46 relaxes the blades are moved back to initial position. My present invention eliminates the skilled use of scissors for cutting hair, and with "steps" in hair as the clippers which trim the hair will do its work lightly and smoothly while those which cut the hair will cut deeply therein, as one clipper bears flat on the head to cut deeply while the other bears at the proper pitch to trim deeply at the apex of the comb and gradually trims the hair more lightly because located farther away.

What I desire to claim and secure by Letters Patent is:

1. A device of the kind described consisting of oppositely sloping fixed combs forming a continuous serrated surface, comb-shaped hair cutting

blades designed in unison to make a rectilinear traverse longitudinally of the comb from end to end thereof, and lever-actuated means for operating said blades.

2. In combination a pair of oppositely and angularly disposed hair clipping cutters adapted to move towards and from each other, a unitary fixed comb extending in overlying contact with said cutters and hand operated means adapted to impart motion to the cutters. 5

3. A hair clipper consisting of a casing having opposing angular combs formed upon the sides thereof and having cutter teeth thereon, a pair of flat blades overlying the angular comb sides and having cutter teeth designed to have a side 15 swipe against the adjacent teeth of the comb sides, a fixed handle bar on the casing, a movable handle bar swingingly carried by said casing, resilient means controlling the swinging of the movable handle bar relatively to the fixed 20 bar, and crank means actuated by said movable handle bar and engaging said cutter blades to impart to the latter simultaneous side swipes against the sides of the comb. 10

4. In combination with a V-shaped cutter 25 comb, a pair of oppositely-arranged movable hair cutting clippers having a cutting swipe against the comb from the apex towards the extremities thereof.

5. As a new article of manufacture a segmental clipper casing having a front wall inclining in opposite directions from the center so as to provide a pair of forwardly converging combs, and having its rear wall formed with a slot, and a top flat wall closing the casing and having 35 front edges converging forwardly in spaced parallel relation to said combs so as to provide slits between said edges and said combs. 30
